VARIABLE CAPACITY COMPRESSOR

Original Filed Sept. 17, 1926

FIG. I.

Michael Riesner
INVENTOR

BY *R. Schreyer*

ATTORNEY

UNITED STATES PATENT OFFICE

MICHAEL RIESNER, OF CINCINNATI, OHIO, ASSIGNOR TO WORTHINGTON PUMP AND MACHINERY CORPORATION, OF NEW YORK, N. Y., A CORPORATION OF VIRGINIA

VARIABLE CAPACITY COMPRESSOR

Original application filed September 17, 1926, Serial No. 136,008. Divided and this application filed September 26, 1928. Serial No. 308,359.

This invention relates to means for unloading fluid compressors and broadly to means for automatically unloading the compressor, gradually, when the receiver pressure rises to predetermined degrees, and gradually loading it as the receiver pressure falls, and the primary object of the invention is to provide an apparatus of this type which will be economical in operation, provide a relatively high efficiency compressor and one which will be relatively simple in construction and consequently cheaper to manufacture than those heretofore used.

The present invention contemplates the use in a variable capacity compressor of clearance chambers and by-pass, together with the pressure operated control apparatus to permit the gradual unloading of the compressor cylinder for permitting its operation under various predetermined percentages of its full capacity.

For a full understanding of the invention, a detailed description of the construction embodying the same in preferred form will now be given in connection with the accompanying drawing forming a part of this specification, and which is a diagrammatic view partly in section and partly in elevation of a variable capacity compressor and its regulator or controller constructed in accordance with this invention, and features forming the invention then specifically pointed out in the claims.

The present application is a division from my application, Serial Number 136,008, filed September 17th, 1926.

Referring more particularly to the drawing, A is a compressor cylinder, B the piston and C the piston rod, which is driven in any suitable manner and while no suction or discharge valves are shown in the drawing, it is to be understood that the compressors are provided with suction and discharge valves of approved type, at the crank and head ends of the cylinder A as in the construction of

double acting compressors of approved types.

The compressor cylinder A has clearance chambers 1 and 2, preferably in the walls of the cylinder and these clearance chambers are separated by a partition 3 which has a port 4 therein to establish communication between the chambers. The chamber 1 has communication through a port 5 with the crank end of the cylinder A of the compressor and this port is normally closed by a valve 6 actuated by a pressure operated piston 7 which is moved in its cylinder 8 by pre-determined receiver pressure to open the valve 6 for connecting the crank end of the cylinder A with the clearance chamber 1 for unloading the crank end of the cylinder. The valve 6 is seated by a closing spring 9.

A port 10 establishes communication between the head end of the cylinder A and the clearance chamber 2 and this port 10 is controlled by a valve 11 which is actuated by the pressure operated piston 12. The piston 12 is operated by receiver pressure to open the valve 11 to open the clearance chamber 2 to the head end of the cylinder A for partly unloading the said head end.

The port or opening 4 is controlled by a valve 14 which is actuated by a pressure operated piston 15 which is moved in its cylinder 16 by receiver pressure to open the valve 4 for connecting the clearance chambers 1 and 2 to establish a by-pass between the crank and head ends of the cylinder A to provide complete unloading of the cylinder at which time the compressor will operate at zero capacity.

The pistons, 7, 12 and 15 are automatically controlled by the control apparatus E which includes a piston valve 20 actuated by apparatus controlled by the receiver pressure, as is usual in such unloading devices. The receiver pressure and operation of the valve 20 is preferably secured through a pressure operated piston 21 controlled by a pilot valve 22. The pilot valve 22 is controlled by the pivoted weighted lever 23

which is in turn controlled by suitable pressure actuated mechanism of approved type, and such as shown in my companion application above referred to, and thus the pilot valve 22 is controlled directly by receiver pressure to control the flow of pressure fluid for actuating the piston 21. The pressure fluid used for operating the piston 21 may be of any suitable character and taken from any suitable source thus enabling the apparatus D to be controlled by slight variances in the receiver pressure while employing pressure as heavy as desired for actuating the piston 21. The control apparatus just generically described is more fully illustrated and specifically described in my prior Patents Numbers, 1,579,781 and 1,579,782.

The clearance chambers 1 and 2 may be of any desired capacity so as to unload and load the cylinder A in the steps required, but assuming that the capacity of each clearance chamber is such as to provide one fourth unloading of the cylinder A, the operation of the construction is, as follows: assuming that the compressor is operated at full capacity, an increase in receiver pressure above that for which the apparatus is set will operate the control apparatus and will permit fluid under pressure to pass from the pipe 24 through the cylinder 26 and pipe 27, passing from the pipe 27 through the branch pipes 28 and 29 against the inner sides of the pistons 7 and 12 for simultaneously actuating the valves 6 and 11 and opening both the crank and the head end of the cylinder A to their respective clearance chambers 1 and 2 thus partly unloading the crank and head ends of the cylinders so that the compressor operates at 50% capacity or other capacity depending upon the size of the clearance chambers.

On a further increase of receiver pressure, the operation of the control apparatus E is repeated and the fluid under pressure is permitted to flow from the pipe 24 through the cylinder 26 and the pipe 30 against the inner surface of the piston 15, to open the valve 14 and connect the clearance chambers 1 and 2 to form a by-pass between the crank and head ends of the cylinder so as to completely unload both ends of the cylinder, at which time the compressor operates at zero capacity.

The loading of the compressor cylinder A is by reverse operation of the various mechanisms to the unloading operation; that is, upon decrease in receiver pressure the control apparatus E operates to cut off communication between the pipes 24 and 30 and relieves the piston 15 of pressure, the pressure fluid bleeding from the pipe 30 out through the cylinder 26, which permits the valve 14 to be seated and permits operation of the compressor at 50% capacity.

Further decrease of the receiver pressure operates the control apparatus E and cuts

off the delivery of fluid under receiver pressure through the pipe 27 thereby relieving the pistons 7 and 12 of pressure and permitting the valves 6 and 11 to be seated, thereby permitting operation of the compressor at full or 100% capacity.

It will be understood that the invention is not to be limited to the specific construction or arrangement of parts shown but that these may be modified widely within the invention defined by the claims.

What is claimed is:

1. In a variable capacity compressor, the combination with a cylinder, of a plurality of clearance chambers, and pressure controlled means for partially unloading said cylinder by simultaneous opening of said clearance chambers to the cylinder, and for wholly unloading the cylinder by opening the clearance chambers to each other.

2. In a variable capacity compressor, the combination with a cylinder, of a clearance chamber for unloading the crank end of the cylinder, a clearance chamber for unloading the head end of the cylinder, and pressure controlled means for simultaneously opening communication between said clearance chambers and the cylinder for wholly unloading the cylinder.

3. In a variable capacity compressor, a combination with a cylinder, of a clearance chamber for unloading the crank end of the cylinder, a clearance chamber for unloading the head end of the cylinder, and pressure controlled means for simultaneously opening communication between said clearance chambers and the cylinder for partly unloading the cylinder, said pressure controlled means further opening communication between said clearance chambers for wholly unloading the cylinder.

4. In a variable capacity compressor, the combination with a cylinder, of a clearance chamber for unloading the crank end of said cylinder, a clearance chamber for unloading the head end of said cylinder, a partition between said clearance chambers and provided with a by-pass port to permit communication of the clearance chamber for wholly unloading the cylinder, pressure operated valves controlling communication between the cylinder and said clearance chambers, a pressure operated valve controlling said opening for establishing communication between the clearance chambers, and pressure controlled means for operating said cylinder and clearance chamber control valves simultaneously for partial unloading of the head and crank ends of the cylinder and for opening said by-pass port subsequently to the opening of the cylinder and clearance chamber valves for wholly unloading the cylinder.

5. In a variable capacity compressor, the combination with a cylinder, of a plurality of clearance chambers, and pressure controlled

means for partially unloading said cylinder by simultaneous opening of said clearance chambers to the cylinder and for wholly unloading the cylinder by opening the clearance chambers to each other, said pressure controlled means being independent of the suction or discharge valves of the compressor whereby the loading and unloading of the compressor will be independent of operation of either the suction or discharge valves.

In testimony whereof I affix my signature.

MICHAEL RIESNER.
